UNITED STATES PATENT OFFICE

ELLIOT SAVAGE, OF WEST MERIDEN, CONNECTICUT, ASSIGNOR TO JULIUS PRATT & CO.

MACHINE FOR GAGING AND TOOTHING IVORY FOR PIANOFORTE-KEYS.

Specification of Letters Patent No. 32,967, dated July 30, 1861.

To all whom it may concern:

Be it known that I, ELLIOT SAVAGE, of West Meriden, county of New Haven, State of Connecticut, have invented a new and useful Machine for Planing and Tooothing Ivory Plates for Piano-Keys; and I do hereby declare that the following is a full, clear, and exact description of the same, reference being made to the annexed drawing, making 10 a part of this specification, in which—

Figure 1 is a top view, Fig. 2 an end elevation, and Figs. 3, 4, 5 and 6 parts in detail.

Similar letters indicate similar parts 15 throughout the figures.

My improvement has for its object the tooothing and gaging piano-forte ivory by machinery and automatically.

Ivory blanks for the finger keys of piano 20 fortés, organs and similar instruments consist of plates of ivory sawed from the tooth or tusk as near to the size and thickness of the finished piece as can conveniently be done, these pieces are then bleached, which 25 process is a slow tedious one, being accomplished entirely by the sun's rays. After being bleached the blanks are assorted by the manufacturer into sets, and in that manner go to the "key maker." In applying the 30 ivory to the keys two things are important first to prepare the blanks for taking the glue by which they are held to the wood of the keys, and second to match for color and to level the surface; all which is done before 35 sawing the key-board into separate keys. To enable the ivory to hold the glue each blank must undergo the operation of toothing. This consists in cutting a series of fine channels or parallel grooves along what is 40 to be the under side by means of a plane, having a toothed or grooved plane iron. The ivory is then ready for gluing down. After matching the pieces for color in the rough it often happens that in leveling, the 45 reduction of a thick piece so alters its color as to require it to be taken off and replaced by another, and thus waste of time and materials take place.

By my invention I reduce all the ivory 50 blanks to an exact thickness and also tooth them at the same operation. From this there results some additional advantages besides the getting rid of the labor of toothing by hand and the risk of alteration of color, viz, 55 the reduction in the time required to bleach the pieces to about one half; as by reason of

the tooth marks that side which is to be uppermost is always known, hence it is only required to bleach one side instead of both as at present.

The machine consists of a set of revolving tooothing planes or irons, placed upon a frame, in such manner that the ivory blanks, which are fed along upon a slide or table, will receive their action and undergo the 60 operation of tooothing and reduction to a gage thickness at the same time. At (a) is shown the tooothing irons. These consist of bars of steel having a series of grooves cut along one face from end to end as at (a') 65 Fig. 6. The proper bevel is then ground on the cutting end and the piece is ready to be placed in its stock. The stock consists of a revolving plate (b) having mortises in the rim to receive the planes which are then secured in place by a clamp ring (c) as shown 70 in Figs. 1 and 2. These tools must revolve exactly in the same plane so that the tooothing grooves formed by the passage of one tool will lie exactly in the path of the 75 80 grooves in the tool which follows so as to prevent cross cutting and to insure the parallelism of the grooves, from end to end, of the ivory. The ivory blanks are brought to the revolving plane irons by a carrier which 85 consists of a slide bar (d) playing in a guide groove in the bed plate of the machine, as shown at (d'), and which carrier passes beneath the planes. At one end of (d) there is a recess seen at (e) Figs. 4 and 5 a little 90 shallower than a blank is thick, on the top there is a rack (f) by means of which the carrier is moved back and forth in the slide, through the agency of a pinion (f') as 95 shown.

At (g) is shown the feeder, for holding the ivory blanks, to be toothed and gaged to thickness. This is a tube, or channel, standing vertically, and is placed directly over the carrier (d) just back of the planes. 100 The square of the tube inside is of a size and shape to receive the ivory blanks, lying flat, so that when filled it constitutes a pile of them, as seen in Figs. 2, 4 and 5 at (g'). The bottom of this tube is formed by the 105 surface of the carrier, consequently the lowest piece of ivory rests upon it always. The carrier may be made to slide to and from the planes by any suitable mechanism. In the drawings a belt (h) from the main shaft 110 A drives a shaft with a worm wheel and from which revolution is given to a cam (j).

This vibrates a sector (*k*) gearing into a pinion (*l*), shown in dotted lines in Fig. 2, upon the shaft which has the large pinion (*f'*) upon it.

- 5 The operation is as follows: The shaft *A* is made to revolve in the direction of the arrow, this causes the train of mechanism just described, to be set in motion and cause (*f'*) to turn and draw along the carriage 10 (*d*). The recess (*e*) will now be brought under the feed tube, when an ivory blank (*g'*) will drop into it. The motion by the action of the cam (*j*) is now reversed and the carrier advances toward the revolving 15 cutter and in doing so takes with it the ivory piece in the recess, as seen at (*g''*) Figs. 2, 4, and 5. As the ivory approaches the cutters (*a*) their toothed edges begin to act upon its surface, planing it down to a thickness and at the same time leaving 20 their tooth marks. As the piece progresses these form continuous lines or grooves from end to end. After the ivory has passed completely under the tool the cam again 25 reverses the motion of (*f'*) and the carrier begins to be withdrawn. The piece of toothed ivory in the recess (*e*) must now be discharged, this is merely thrown off the end of the bar or carrier (*d*) by a spring piece 30 (*o*), Fig. 5 which strikes the end of the ivory projecting above the level of (*d*) and pre-

vents it from returning with the carrier and it accordingly glides from under, when the blank drops off the table. The recess (*e*) once more comes beneath the feed tube and 35 receives another blank and the work goes regularly on.

At (*p*) is a spring finger the use of which is to press upon the ivory just behind the planes and thus prevents it from jumping 40 out of its recess. The ivory for the tails of the key are usually made thinner at one end, than the other, to plane and tooth these the recess (*e*) must be inclined on the bottom so as to maintain a level surface while going 45 under the plane irons.

What I claim is—

The toothing and gaging the ivory blank by means of a series of revolving toothed irons, placed in a revolving stock so that the tooth points of each will lie in the same planes; and in combination therewith of a carrier operating in such manner as to feed the ivory blanks to the planes automatically substantially in the manner and for the purpose set forth herein. 50 55

In witness whereof I have hereto set my hand and seal.

ELLIOT SAVAGE. [L. S.]
